UNITED STATES PATENT OFFICE.

LEON BLOCH, OF CLEVELAND, OHIO, ASSIGNOR TO THE REPUBLIC BRASS COMPANY, OF CLEVELAND, OHIO, A CORPORATION OF OHIO.

FOUR-WAY DIVERTER VALVE.

Original No. 1,579,503, dated April 6, 1926, Serial No. 33,137, filed May 27, 1925. Application for reissue filed October 19, 1926. Serial No. 142,740.

This invention relates generally to plumbing fixtures and more particularly to a novel construction of valve used in connection with a bath tub and shower.

5 The object of the invention is to provide a valve which will serve as a diverter valve, that is to say a device that can be used in connection with inlet valves (not shown) to deliver to the tub or shower the water at any 10 desired temperature, either all hot, all cold or mixed and modified.

Another object of the invention is to provide a valve of this character which will be of simple and economical construction and 15 in which the parts can be readily replaced or repaired, if necessary.

With these objects in view and certain others which will become apparent as the description proceeds, the invention consists 20 in the novel features of construction and in the manner of combining or arranging the same all of which will be fully described hereinafter and set forth in the appended claims.

25 In the drawings forming a part of this specification, Fig. 1 is a sectional view of a valve constructed in accordance with my invention and illustrating the manner of arranging the same; Fig. 2 is a detail sectional view taken on the line 2-2 of Fig. 1 and looking in the direction of the arrows; and Fig. 3 is a detail sectional view taken on the line 3-3 of Fig. 1 and looking in the direction of the arrow.

30 In the practical embodiment of my invention I employ a valve casing A having an outlet B at one side and an outlet C at the opposite side, one of the outlets leading to a shower and the other outlet being adapted to be connected to a bath tub, an inlet D adapted to be attached to a hot water supply and an inlet E adapted to be attached to a cold water supply. The casing is divided into two compartments by means of 35 partitions F and G and these partitions form in effect an inlet chamber into which the hot and cold water are delivered. The casing is also formed with a tubular extension or housing H which is adapted to extend into the opening I produced in the wall or tiling K.

The partition F has an opening F', the edges of which are finished to provide a valve seat for the valve L carried at the end

of the stem L' and provided at its outer end with the operating handle L². The stem L' of the valve is provided with threads L³ which engage the threads M³ of a sleeve M screwed into the housing H and into the threaded opening G' produced in the partition G.

The tubular extension or housing H is slightly enlarged at H' in order to provide an annular space between the inner end of the sleeve M and the lateral extension of the valve casing and the extreme inner end of the sleeve M is finished to provide the valve seat M' upon which the valve L can seat when said valve is shifted from the position shown in Figs. 1 and 2.

40 The sleeve M is provided with ports M² which establish communication between the interior of the sleeve and the enlarged portion H' of the housing, which housing communicates through the connection B with a shower outlet (not shown); it being understood that water from the inlets D and E passes through the opening in the valve seat M' in the sleeve M, when the valve L is moved to the position shown in Figs. 1 and 2, and thence through the ports M² into the enlarged portion H' of the housing and thence out the connection B.

45 The joint between the casing extension H and the sleeve M is suitably packed, and surrounding the stem L' and screwing into the outer end of the sleeve M is a gland N. Screwing into this gland N is a sleeve O threaded externally to receive a cap P which is flanged for engagement with the porcelain escutcheon Q which surrounds and conceals the valve and also the opening in the wall or tiling in which said valve is arranged.

50 It will thus be seen that I provide a valve casing having inlets for the hot and cold water and outlets for the tub and shower and by moving the valve to seat in the opening in the partition F the outlet C will be cut off and the outlet B will be opened allowing the water to pass to the shower and by shifting the position of the valve the outlet B will be closed and the outlet C will be opened allowing the water to pass to the tub, it being understood of course that the supply of hot and cold water to the valve is controlled by separate valves in the hot and cold water pipes (not shown).

55 The valve is exceedingly simple consist-

ing of the casing and lateral extension and sleeve arranged therein, one valve seat being carried at the inner end of the sleeve and the other valve seat in the partition in the cas-
5 ing.

By means of the packings arranged as de-
scribed, all danger of leakage is avoided and
the construction of the valve also lends itself
to the employment of the concealing es-
10 tucheon which not only conceals the valve
proper but also the opening in the wall or
tiling in which the same is arranged.

It will thus be seen that I provide an ex-
ceedingly simple and economical form of a
15 valve and particularly adapted for use in
connection with tub and shower fixtures for
providing the proper mixing of the hot and
cold water.

Other modes of applying the principle of
20 my invention may be employed instead of
the one explained, change being made as re-
gards the mechanism herein disclosed, pro-
vided the means stated by any of the follow-
25 ing claims or the equivalent of such stated
means be employed.

I therefore particularly point out and dis-
tinctly claim as my invention:—

1. In a valve, the combination of a casing
20 having two inlet and two outlet openings
disposed in the same plane and said outlet
openings being disposed on opposite sides of
said casing, two spaced interior partitions in
said casing defining a diverter chamber sepa-
25 rated from said outlet openings but in com-
munication with said inlet openings, said
partition having aligned ports therein, and
said casing having angular passages extend-
ing from said aligned ports to said outlet
30 openings respectively, a hollow sleeve dis-
posed in said casing and having a lateral
port establishing communication between one
of said angular passages and said diverter
chamber, and a valve disposed between said
35 aligned ports and movable into a position
closing either thereof to divert the flow of
liquid through the other of said ports.

2. In a valve, the combination of a casing
having a lateral extension, said casing hav-
ing two inlet and two outlet openings dis-
posed in the same plane and said outlet
openings being disposed on opposite sides of
50 said casing, two spaced interior partitions in
said casing defining a diverter chamber sepa-
rated from said outlet openings but in com-
munication with said inlet openings, said
partitions having aligned ports therein, and
55 said casing having angular passages extend-
ing from said aligned ports to said outlets
respectively, a hollow sleeve disposed in the
extension of said casing and having a por-
tion spaced from the wall of said casing and
60 provided with a lateral port establishing
communication between one of said angular
passages and said diverter chamber, and a
valve disposed between said aligned ports
and movable into a position closing either
65 thereof to divert the flow of liquid through
the other of said ports.

3. In a valve, the combination of a casing
having two inlet and two outlet openings
70 disposed in the same plane, the two outlet
openings being disposed in opposite sides of
said casing, two spaced interior partitions in
said casing defining a diverter chamber sepa-
rated from said outlet openings but in com-
75 munication with said inlet openings, said
partitions having aligned ports therein, and
said casing having spaced substantially par-
allel angularly arranged passages extending
from said aligned ports to said outlets re-
spectively, a hollow sleeve disposed in said
casing and having a lateral port establishing
communication between one of said angular
passages and said diverter chamber, and a
valve disposed between said aligned ports
85 and movable into a position closing either
thereof to divert the flow of liquid through
the other of said ports.

Signed by me, this 11th day of October,
1926.

LEON BLOCH.
